UNITED STATES PATENT OFFICE

JAMES J. HENNESSY, OF NEW YORK, N. Y.

JOURNAL LUBRICATOR

Application filed November 12, 1927. Serial No. 232,829.

My invention relates to journal lubricators of the type particularly adapted for use in railway rolling stock and consists of a device including a lubricant reservoir and a member, actuated by relative movement of the device and the journal, for feeding a lubricant applicator from the reservoir to the journal.

10 The object of my invention is to provide a feeding mechanism which will be certain in operation and will supply lubricant to the journal by means of a moving belt as distinguished from pumping a stream of lubricant to the journal.

15 In the accompanying drawings which illustrate my invention—

Figure 1 is a section through a driving box cellar including my device and the adjacent journal and hub with which the device is assembled.

Figure 2 is a transverse section taken substantially on the line 2—2 of Figure 1.

Figure 3 is a transverse section taken substantially on the line 3—3 of Figure 1.

20 Figure 4 is a transverse section through a modified structure.

Figure 5 is a section on line 5—5 of Figure 4.

25 Figure 6 is a section corresponding to Figure 5 illustrating another modification of my invention.

Figure 7 is a section taken substantially on the line 7—7 of Figure 6.

30 Figures 8 and 9 are longitudinal and transverse sections, respectively, through a modified structure, Figure 8a being a horizontal section illustrating a detail.

35 Figures 10 and 11 are transverse and longitudinal sections respectively through another modification of my invention.

A journal A indicated in Figure 1 is provided with a wheel B, the hub of which extends radially of the journal and the journal supports the truck or frame of the locomotive or other rolling stock to which it is applied in any ordinary manner, the details of which form no part of my invention and are not illustrated but which will include a pedestal within which the cellar is carried as is well understood in the art.

My cellar includes a bottom 1 and side walls 2, the lower portion of which cellar forms a reservoir for lubricant 3. I prefer to use an endless belt 4 as the means for supplying lubricant to the journal, and in the preferred form illustrated in Figures 1, 2 and 3 this belt is shown as passing over rollers 5, 6 and 7. Roller 5 is journaled in brackets 8 formed integrally with one of the side walls 2 of the cellar. Roller 6 is journaled on yielding elements 9 mounted on the other side wall of the cellar and roller 7 is hollow throughout its length and is journaled upon a rod 10 which extends through the end walls 11 and 12 of the cellar and is adapted to be reciprocated lengthwise and may be termed a contact rod as its outer end 13 is adapted to contact with the hub B on the wheel of the journal. The opposite end 14 of rod 10 is squared and is received in a cap 15 provided with a spring 16 which tends to thrust rod 10 to the left.

In all railway journals of this type there is substantial play of the axle lengthwise in its box and I utilize this play of the axle to move the contact rod 10 in one direction, spring 16 functioning to move the rod in the opposite direction whenever the movement of the journal so permits.

To translate this reciprocal movement of the rod into rotary movement of roller 7, I provide the surface of the rod with a series of short fixed ribs or blades 17 inclined to the axis of the rod. The adjacent portion of roller 7 is enlarged to form a housing as indicated at 18. A series of pawls 19 are provided on the sides of this housing and are spaced unevenly about the inner periphery of housing 18 so that at least one of the pawls 19 will always be engaged by one of the ribs 17. Movement of the rod 10 to the left will rotate at least one pawl on its pivot until the end of the pawl engages the inner periphery of the housing 18 when further movement of the pawl by the contact rod 10 will rotate the roller 7 about the axis of the roller and rod. A ratchet and pawl 20 is arranged to check return movement of the roller and insure the same being advanced continuously in one direction.

Preferably roller 7 is provided with teeth 100

21 or similar elements for engaging belt 4 and moving the latter. The movement of the belt through the lubricant reservoir and over rollers 5 and 6 will carry lubricant to 5 the journal A, the bottom of which is below the level of the tops of rollers 5 and 6. The yielding mounting 9 for roller 6 will place the belt under suitable tension and this tension may be made any degree desired.

10 In order to avoid the wasteful discharge of surplus lubricant, I prefer to provide wipers 22 in the form of rollers yieldingly held in contact with the journal A, by means of springs 23, and positioned above the level of 15 rollers 5 and 6.

My invention may be embodied in numerous forms and I illustrate one of such modifications in Figures 4 and 5 in which the lubricant reservoir 24 is provided with an 20 extension 25 in which is mounted a weight 26 yieldingly supported by a spring 27 and provided with an upstanding element 28 carrying a pair of pawls 29 adapted to engage 25 opposite sides of a ratchet 30 which is carried on a shaft 31 mounting a roller 32 corresponding to the roller 7 shown in Figures 1, 2 and 3.

This device, instead of relying upon the lateral movement of the journal in its cellar, 30 is actuated by the successive impulses, given to the weight 26, caused by vertical jars such as results from a wheel passing over a rail joint and the complementary movement of the weight by the spring 27.

35 In the structure shown in Figures 6 and 7 I utilize a swinging pendulum 33 pivoted at 34 on a bracket 35 and this pendulum is provided with flexible arms 36 adapted to engage the teeth of a ratchet 37 mounted on 40 the shaft 38 of a roller 39 which is adapted to rotate the lubricating belt similar to that shown in Figures 1, 2 and 3. This operating mechanism is mounted in a compartment 40 corresponding to compartment 25 shown 45 in Figures 4 and 5.

The swaying of the truck with which the device is assembled will cause oscillating movement of the pendulum 33 resulting in alternate upward and downward movement 50 of the arms 36 and resulting rotation of ratchet 37.

In each of the structures shown in Figures 4 to 7 there will be no necessity of a check 55 ratchet and pawl as the devices are double-acting and feed the roller irrespective of the direction of movement of the weight 26 over the pendulum 33.

In the structure shown in Figures 8, 8a, and 9, the side walls 41 of the cellar are provided with fixed brackets 42 on which are 60 mounted idler rollers 43 and the lubricating belt 44 passes over rollers 43 and carries a third idler roller 45, the weight of which holds the horizontal portion of the belt 65 against the undersurface of the journal J

and, as the amount of lubricant on the surface of the journal decreases, friction between the journal and the belt will result in the belt being driven by the journal so as to feed lubricant from the reservoir to the 70 journal.

The ends of roller 45 are provided with flanges 46 which retain the roller in position and I prefer to provide a rib 47 on the bottom wall of the cellar, adjacent the inner 75 face of one of the flanges 46, and to provide a spring 48 bearing against the opposite face of the flange 47. In this manner, I can frictionally retard the rotation of roller 45 and thereby decrease the amount of lubricant 80 which is delivered to the journal.

In the structure shown in Figures 10 and 11, I utilize a pendulum but instead of the same swinging longitudinally of the journal, it is arranged to swing transversely thereof and it is therefore actuated by uneven movements of the truck along the rail, instead of movements across the rail. In this structure, the pendulum 49 is suspended from the top wall of the compartment 50 at the side of the cellar and pawls 51 and 52 are pivoted on the pendulum supporting element 53 and engage opposite sides of a ratchet 54 mounted on the end of the belt of the feeding roller 55. Movement of pendulum 49 to the right will result in rotation of ratchet 54 and roller 55 through the action of pawl 51, pawl 52 riding over the upper teeth of the ratchet. Movement of pendulum 49 in the opposite direction will rotate ratchet 54 and roller 55 100 in the same direction, pawl 51 riding over the lower teeth of the ratchet.

Obviously, other variations in structure could be accomplished without departing from the spirit of my invention, and I contemplate the exclusive use of all such modifications as come within the scope of my 105 claims.

I claim:

1. In a journal lubricating device for a 110 railway journal box, a lubricant reservoir, a belt, elements for guiding said belt into said reservoir and into contact with the journal with which the device is assembled, and means actuated by relative bodily horizontal shifting movement of said journal and the device in the box for moving said belt over said elements.

2. In a journal lubricating device, a lubricant reservoir, rollers positioned in said reservoir and above the level occupied by the bottom of a journal with which the device is assembled, a belt extending over said rollers, and means operated by longitudinal shifting of the journal relative to said rollers for moving said belt on said rollers.

3. In a journal lubricating device, a lubricant reservoir, rollers journaled on opposite sides of said reservoir at a higher level than that occupied by the bottom of a journal with 130

which the device is assembled, a roller journaled below the normal level of lubricant in said reservoir, a belt passing around said rollers, and means operated by longitudinal shifting of the journal relative to said rollers for moving said belt over said rollers.

4. In a journal lubricating device, a lubricant reservoir, rollers journaled on opposite sides of said reservoir at a higher level than 10 that occupied by the bottom of a journal with which the device is assembled, a roller journaled below the normal level of lubricant in said reservoir, and means for moving said belt over said rollers comprising a reciprocating 15 bar adapted to be engaged by an annular surface extending from said journal, to be moved in one direction, a spring for moving said bar in the opposite direction, and interengaging elements on said bar and one of said rollers 20 for rotating the latter when said bar is reciprocated.

5. In a journal lubricating device, a lubricant reservoir, a reciprocating bar, inclined ribs on said bar, a roller element, a plurality 25 of pawls pivotally mounted on said element and having teeth in engagement with said ribs and adapted to be rotated by reciprocal movement of said ribs, a check pawl and ratchet preventing movement of said roller in 30 the direction opposite to that induced by said ribs and pawls, and a belt mounted on said roller to feed lubricant from said reservoir to a journal with which the device is assembled.

35 6. In a journal lubricator, a body with spaced walls and including a lubricant reservoir, a rod slidably and non-rotatably mounted in said walls and adapted to project through one of them so as to contact with an 40 annular element on a journal to be lubricated, to move said rod in one direction, a spring for moving said rod in the opposite direction, a hollow roller surrounding said rod and rotatable thereon, inclined ribs on said rod near 45 one end, an enlarged housing on said roller adjacent to and surrounding said ribs, a plurality of swinging pawls on the interior of said housing and in engagement therewith and adapted to retain said roller when engaged by said ribs when said rod is moved in 50 one direction, a ratchet and pawl for preventing rotation of said roller in the opposite direction, and a belt mounted on said roller and movable thereby through said reservoir and against said journal.

7. In a lubricant device, a lubricant reservoir, a rod slidably mounted in said reservoir, a hollow roller journaled on said rod, interengaging elements on said rod and roller 60 for rotating the latter when said rod is reciprocated, a belt mounted on said roller and leading from the bottom portion of said reservoir to an elevated point thereon where it forms contact with a journal with which the device is assembled.

8. In a journal lubricating device, a lubricant reservoir, an endless belt, elements for guiding said belt into said reservoir and into contact with the journal with which the device is assembled, and reciprocating means 70 actuated automatically by the operation of the journal for moving said belt over said elements.

In testimony whereof I hereunto affix my signature this 6 day of October, 1927.
